LET-OFF MECHANISM

William H. Bahan, Greenville, S. C.

Application May 13, 1940, Serial No. 334,921

5 Claims. (Cl. 139—100)

This invention relates to a let-off mechanism for looms which is employed for maintaining a uniform tension in the warp prior to the same being woven into cloth. It is a well known fact that great difficulty has been encountered in maintaining uniform warp tension due to the fact that the diameter of the wound material upon the warp beam gradually diminishes as the warp is used. As the diameter decreases, there is a necessity for a corresponding decrease in the restraining means for the beams; otherwise the tension of the warp will increase as the diameter of the material on the warp beam decreases.

It is an object of this invention to provide a mechanism for decreasing the restraining influence upon the beam in direct proportion to the decrease of the diameter of the material wound thereon. Specifically, I have employed a rotatable element for resisting the let-off of the warp beam, the rotation of which is adapted to be resisted by a loose weighted material. Means are provided for varying the amount of the material in which this element is adapted to rotate so that the proper amount of resistance will be offered to the let-off of the beam regardless of the diameter of the material from thereon.

Some of the objects of the invention having been stated, other objects will appear as the description proceeds, when taken in connection with the accompanying drawing, in which—

Figure 1 is an elevation showing certain portions thereof in section, illustrating my improved let-off mechanism, associated with a loom;

Figure 2 is a vertical sectional view taken along the line 2—2 in Figure 1;

Figure 3 is a sectional view similar to the lower central portion of Figure 1, illustrating the action of loose weighted material as it resists the let-off of the warp beam.

Referring more specifically to the drawing, the numeral 10 designates a loom frame having a warp beam 11 with a warp material 12 wound thereon. This warp material 12 is drawn from the beam in a sheet form designated by the reference character 13, which warp passes upwardly over roller 14 and then through conventional stop motion drop wires 15. After passing through these wires, the warp 13 is divided into sheds, namely, 13a and 13b, each shed passing through a suitable harness heddle 16. In the drawing, one harness heddle is shown in raised position and the other in a lowered position. The sheds 13a and 13b then pass through a conventional reed 17a of loom lay 17 and is formed into cloth 19 in a conventional manner due to

the reciprocatory motion of a shuttle 18 which places the filling between the sheds. The cloth 19 passes over rollers 20 and 21 and then is wound upon the cloth take-up beam 22.

The parts thus far described are conventional in association with most looms which are employed for weaving cloth. The head of the warp beam 11 has integral therewith a gear 23. This gear is adapted to mesh with a pinion 24 on shaft 25, said shaft being rotatably mounted in a bearing 26 secured to framework 10 (Figure 2). The other end of the shaft 25 has a hub member 28 fixedly secured thereon, which hub member has radially extending vanes or paddles 29. The hub 15 and the vanes 29 are encased in a suitable housing 27. It will be noted by referring to Figures 1 and 3 that the extremities of the vanes 29 are adapted to scrape or come into close contact with the interior periphery of the housing for the major portion of the circumference. Also the sides of the vanes are adapted to move in close proximity with the interior sidewalls of the housing. A portion of the interior periphery of the housing however, extends away from the path 20 normally travelled by the ends of the vanes 29, thereby forming a cavity or recess 35, adjacent to the upwardly moving vanes. Within the housing 27 a suitable loose weighted matter 30 such as shot or steel balls is adapted to be placed. 25 As the cloth is woven the warp beam 11 and gear 23 are rotated in a clockwise manner due to the pull of the warp, thereby rotating the pinion 24, shaft 25, and paddles or vanes 29 in a counter-clockwise manner. Since the lower portion 30 of the casing or housing 27 is filled with loose weighted matter such as steel balls 30 it is evident that a resistance to the travel of the vanes will be offered. In other words, the resistance to the let-off of the beam is offered by virtue of 35 the weight of steel balls 30 resting upon the vanes as the vanes move from lowermost to uppermost position. When the vanes approach their uppermost position, the balls supported thereby will fall by gravity downwardly over the hub portion 28 and through openings 29a and 29b which are disposed between the hub and the interior of the housing. The vanes, upon their downward travel, have none or almost only a relatively small amount of weighted matter resting thereon, because the balls will fall downwardly through opening 29a and 29b to the lower portion of the housing, and get in front of the lower vanes.

As heretofore stated, it is desirable to decrease 50 the resistance offered to the turning of the warp

beam as the diameter of the material 12 on the beam decreases. The proper reduction of the resisting force will maintain an even tension in the warp 13. In order to provide this means for varying the resistance offered to the turning of the warp beam, a lever 38 has been fixedly secured to a shaft 39, the upper end of said lever being adapted to contact at all times, the periphery of the wound material 12 upon the beam 11. The shaft 39 to which lever 38 is attached, is rotatably mounted in a bracket 40, which, in turn, is supported by the framework 10 of the loom. The other end of the shaft 39 has fixedly secured thereon, a lever 41 and the free end of this lever has pivoted thereto as at 42 a vertically disposed link 43. The upper end of the link 43 is pivoted as at 44 to the face of the housing 27. As the diameter of the material 12 decreases, it is seen by referring to Figure 1 that the upper end of lever 38 will move toward the axis of rotation of the beam, thereby rotating the lever 41 and shaft 39 in a counterclockwise manner and at the same time rotating the housing 27 in a clockwise manner to the dotted line position indicated by reference character 27b. This position of the housing will place more of the eccentric recess 35 out of the line of travel of the vanes 27 as they move upwardly: consequently a less amount of weighted material will be disposed above these vanes, resulting in a corresponding decrease in the amount of resisting force offered to the turning of beam 11.

On the other hand, if the beam 11 is filled with material 12 and it is necessary to create a greater resisting force in order to maintain a uniform tension in the warp 13, the housing 27 will be rotated to the dotted line position 27a. This position will be occupied by the housing, because the upper end of the lever 38 will rest a farther distance from the axis of rotation of the warp beam 11. When the recess 35 of the casing 27 is disposed more directly above the upwardly travelling vanes 29, there is a greater amount of material pressing downwardly against the vanes, thereby offering a greater resistance to the turning of the vanes and also to the turning of the warp beam 11.

When it is desired to vary the initial position of the housing 27, it is only necessary to remove the bolt 42 and insert it into other coinciding holes 45 and 46 in levers 41 and 43 respectively.

In order to provide ready access to the interior of the housing 27, a door 48 is pivoted as at 49 to the upper side thereof.

It is therefore seen that I have provided a means for maintaining a uniform tension in the warp as it is let off from a warp beam, regardless of the diameter of the material on the beam.

In the drawing and specification there has been set forth a preferred embodiment of the invention, and although specific terms are employed, they are used in a generic and descriptive sense only and not for purposes of limitation, the scope of the invention being set forth in the appended claims.

I claim:

1. In a warp tensioning device for looms, a

warp beam, a shaft driven by said beam, a plurality of radially disposed vanes extending from said shaft, and being adapted to have loose weighted matter to resist rotation, and a housing 5 separate from the vanes and encasing said vanes and said weighted matter, and means for adjusting the position of the housing relative to the vanes and said shaft.

2. In a warp tensioning device for looms, a 10 warp beam, a shaft driven by said beam, a plurality of radially disposed vanes extending from said shaft, and being adapted to have loose weighted matter to resist rotation, a housing enclosing said vanes for containing said weighted matter, and means adjusting the position of the housing relative to the vanes for varying the resistance offered by the loose weighted matter to the rotation of the vanes.

3. In a warp tensioning device for looms, a 20 warp beam, a plurality of radially disposed carriers, a relatively stationary housing encasing the carriers and being adapted to support weighted loose matter, means driven by the warp beam for rotating the carriers to lift the weighted matter as some of the carriers move upwardly, and for releasing the material as the material approaches the top of the casing, and means for adjusting the position of the housing relative to the vanes to thereby regulate the amount of resistance offered by the weighted matter to the rotation of the vanes.

4. In a warp tensioning device for looms, a 30 warp beam, a shaft driven by said beam, a plurality of radially disposed vanes extending from said shaft, and being adapted to have loose weighted matter to resist rotation, a housing enclosing said vanes in said weighted matter, said housing having an eccentrically disposed cavity adjacent said vanes as they travel upwardly, means for allowing a portion of said matter carried by the upwardly moving vanes to move into said cavity and for allowing the remainder as it approaches the top to fall on the downwardly moving vanes, and means for rotating said cavity 40 relative to said vanes to thereby vary the amount of matter engaged by the vanes and to vary the amount of matter forced into the cavity.

5. In a warp tensioning device for looms, a 50 warp beam, a shaft driven by said beam, a plurality of radially disposed vanes extending from said shaft, and being adapted to have loose weighted matter to resist rotation, a housing enclosing said vanes and said weighted matter, said housing having an eccentrically disposed cavity adjacent said vanes as they travel upwardly, and means for allowing a portion of said matter carried by the upwardly moving vanes to move into said cavity for allowing the remainder as it approaches the top to fall on the downwardly moving vanes, and means engaging the warp on the warp beam for automatically controlling the position of the housing relative to the vanes to thereby control the elevation of said cavity to vary the amount of weighted matter engaged by 60 the vanes.

WILLIAM H. BAHAN.
